UNITED STATES PATENT OFFICE

CYRIL NUTTER ROYLE, OF NEWTON-LE-WILLOWS, ENGLAND

NOTCH FITTING FOR UMBRELLAS

Application filed March 1, 1928, Serial No. 258,371, and in Great Britain March 14, 1927.

The present invention relates to improvements in the furniture of umbrellas.

Notches or slides for umbrellas are known in which an axle channel in a ring receives the heads of ribs passing through radial slots and shrouded by an upstanding convex flange of greater diameter than the ring.

According to the present invention a notch or slider for an umbrella comprises in combination an upstanding flange convex on its exterior and an externally grooved ring provided with radial slots to receive the ribs, which ring is of lesser diameter than said upstanding flange.

The invention is more particularly described with reference to the accompanying drawings in which:—

Figure 1 is a part sectional elevation through an umbrella, to which the devices of the present invention are affixed.

Figure 2 is a plan view of a "notch" according to the present invention.

Figure 3 is a corresponding outside elevation.

Figure 4 is a cross sectional view of a modified form of construction.

Figure 5 is a cross sectional view of a further modification.

In the application to the present invention to a notch as shown in Figures 1 and 3, the sleeve 1 adapted to be secured upon the stick 2 of the umbrella is provided with the usual notches 3, for the reception of the ends of the umbrella ribs 4, which are therein secured by means of soft iron wire 5 in the usual manner.

According to the present invention a flange 6 is provided on the "notch" having a convex outer surface around which the silk or the like fabric 7 of the umbrella is secured by stitching, as is usual, and is enshrouded by the usual cap 9. It will be seen however, that by this invention the necessity of a rosette or fly at this place will be avoided, and the further advantage obtained that the outstanding smooth surfaced flange 6 holds the fabric clear of the ends of the ribs 4 of the umbrella, and so prevents damage to the cover of the umbrella at this place.

The "slider" of the umbrella comprising

a sleeve 10 can similarly be provided with an upstanding flange 11 convex to the exterior and presenting an abutment surface against which the inner ends of the radial ribs 12 can abut, thereby taking strain off the securing wire 13.

Similarly it will be noticed that the usual rosette sometimes employed to enshroud the ends of the ribs of the umbrella at this place, can be avoided as the flange 11 fully protects the user of the umbrella from the danger of pinching the ends of this fingers between the ribs 12 and the notched ring forming part of the slider.

The flanged part of the present invention 6, 11, as the case may be, may be either formed integral with the "notch" or "slider" respectively, or may be formed separately thereto as shown in Figure 4 and secured by riveting, soldering or other means.

The preferred form of the invention is shown in Fig. 5, in which the notches are formed by a circular diametrical cut. This produces an abutment at the upper end of the radial slot, and this abutment is so disposed relative to the groove in which the holding wire of the ribs is placed, that the outer edge of the abutment holds the rib against horizontal withdrawal. In other words, when the rib ends are placed in the radial grooves, there is a pocket which receives and holds the end of the rib in place, and the endwise strain on the rib is taken up by this abutment rather than by the holding wire which retains the ends in place in the holding grooves.

It will be noticed that the devices of the present invention have the advantage that the cover is protected from contact with the sharp edges of the slots, in which the ribs are mounted, and from the rib ends, and further that the usual rosette and the like extra textile parts can be suppressed with elimination of the labour necessary in the mounting of these. Further, the strain on the cover will be more uniformly distributed than with hitherto known constructions.

I declare that what I claim is:—

A stick fitting comprising a sleeve adapted to be secured to the stick, the lower portion of said sleeve having radial rib receiving slots

therein and a peripheral groove intersecting said slots for receiving a wire adapted to pass through apertures in the ends of umbrella ribs for pivotally securing the ribs in the slots, said groove being of such depth and said sleeve being of sufficient thickness so that the rib ends will be housed wholly within the sleeve when the umbrella is closed, and a laterally extending flange on said sleeve intermediate its ends and projecting outwardly beyond said lower portion and forming abutments at the upper ends of said slots for said ribs, the faces of said abutments being inclined inwardly and upwardly and the securing wire adapted to be so disposed that the ends of the ribs when the umbrella is closed extend above the extreme outer edges of the abutments, the upper portions of said sleeves being tapered inwardly from said flange toward its upper end to form a support for the umbrella covering whereby said covering is held away from possible contact with the ribs.

In witness whereof, I have hereunto signed my name this 14th day of February, 1928.
